CLAIM

The ornamental design for a portable cooking kit, substantially as shown and described.

DESCRIPTION

FIG. 1 is an isometric view of a portable cooking kit showing my new design;

FIG. 2 is an end elevational view thereof, the opposite end being a mirror image;

FIG. 3 is a bottom plan view thereof;

FIG. 4 is an isometric view thereof in an opened assembled condition;

FIG. 5 is an isometric view of the case only, shown in an opened condition; and

FIG. 6 is an isometric view of the Thermos, hot plate and cups which are shown separately for clarity of illustration only.
